(57) **CLAIM**

The ornamental design for a device for making gelatin-based food and beverage products, as shown and described.

DESCRIPTION

FIG. 1 is a front view of a design for a device for making gelatin-based food and beverage products according to a first embodiment of the present invention.

FIG. 2 is a back view of the device for making gelatin-based food and beverage products of FIG. 1.

FIG. 3 is a top view of the device for making gelatin-based food and beverage products of FIG. 1.

FIG. 4 is bottom view of the device for making gelatin-based food and beverage products of FIG. 1.

FIG. 5 is a right side view of the device for making gelatin-based food and beverage products of FIG. 1.

FIG. 6 is a left side view of the device for making gelatin-based food and beverage products of FIG. 1.

FIG. 7 is a front-right perspective view of a design for a device for making gelatin-based food and beverage products of FIG. 1

FIG. 8 is a back-left perspective view of a design for a device for making gelatin-based food and beverage products of FIG. 1

FIG. 9 is a front view of a design for a device for making gelatin-based food and beverage products according to a second embodiment of the present invention.

FIG. 10 is a back view of the device for making gelatin-based food and beverage products of FIG. 9.

FIG. 11 is a top view of the device for making gelatin-based food and beverage products of FIG. 9.

FIG. 12 is bottom view of the device for making gelatin-based food and beverage products of FIG. 9.

FIG. 13 is a right side view of the device for making gelatin-based food and beverage products of FIG. 9.

FIG. 14 is a left side view of the device for making gelatin-based food and beverage products of FIG. 9.

FIG. 15 is a front-right perspective view of a design for a device for making gelatin-based food and beverage products of FIG. 9; and,

(Continued)

FIG. 16 is a back-left perspective view of a design for a device for making gelatin-based food and beverage products of FIG. 9.

The solid lines in FIGS. 1-24 illustrate a device for making gelatin-based food and beverage products according to the present invention. The broken lines form no part of the claimed design.
